UNITED STATES PATENT OFFICE.

HERBERT IRVING EMMONS, OF LAWRENCE, MASSACHUSETTS.

LOOM PICKER.

Application filed April 18, 1922. Serial No. 554,562.

To all whom it may concern:

Be it known that I, HERBERT I. EMMONS, a citizen of the United States, residing at Lawrence, in the county of Essex and State 5 of Massachusetts, have invented a new and useful Loom Picker, of which the following is a specification.

This invention relates to loom pickers.

The object is to provide a picker for use 10 in connection with looms comprising a frame or holder readily attachable to any picker stick and adjustable thereon, said frame having means for receiving and holding fillers or impact members for engagement with the nose of the shuttle of the loom, the fillers or impact members being readily renewable when worn from extensive use or interchangeable to present a new and unworn face to the shuttle, the holder 15 being adapted to carry a plurality of relatively thin fillers which may be formed of leather, rawhide, felt, rubber or any other similar or fibrous material.

A full and complete understanding of the 20 invention may be obtained from a consideration of the following detailed description, taken in connection with the accompanying drawing forming a part of this specification, it being understood that while the 25 drawing shows a practical form of the invention, the latter is not confined to strict conformity therewith, but may be changed or modified, so long as such changes or modifications mark no material departure 30 from the salient features of the invention, as specifically pointed out in the appended claims.

In the drawing, in which similar reference characters designate corresponding 35 parts throughout the several figures:

Figure 1 is a detail perspective view of the upper portion of an ordinary picker stick having the improved picker attached thereto;

Figure 2 is a similar view of the frame 40 or holder for the impact members;

Figure 3 is a vertical longitudinal sectional view through the frame or holder having the impact members applied thereto 45 and showing the manner of attachment to the picker stick, the latter being shown in dotted lines;

Figure 4 is a face view of one of the impact members;

Figure 5 is a perspective view, similar to 55 Figure 1, showing a modified form of the invention;

Figure 6 is a detail perspective of the frame or holder shown in Figure 5;

Figure 7 is a vertical, transverse sectional 60 view showing the mounting on a picker stick and on a horizontal guide rod; and

Figure 8 is a horizontal sectional view of the same.

In the constant operation of the highly 65 perfected modern loom for the weaving of cloth or fabrics, the greatest wear is centered on that part of the machine which impels the shuttle back and forth across the lay, and this part, known as the picker, as 70 commonly constructed, has been formed in a manner requiring the complete replacement of the picker when the same has become worn. With the use of the device of the present invention, however, it is possible 75 to change, reverse or renew a single one of a plurality of fillers or impact members carried by the picker frame, so that a new and unworn surface may be presented to the nose of the shuttle.

In Figure 1 of the drawing, there is illustrated the upper portion of an ordinary picker stick 1 formed in the usual manner, to which is applied the metallic holder frame 2, which is composed of some suitable 80 cast metal in the form of a single casting, comprising spaced side walls 3, open at their front ends and connected at their rear ends by a rear wall 4. Extending from the rear wall 4 are other side walls 5 preferably arranged slightly closer together than the aforesaid open-ended walls 3 and formed integrally therewith, the walls 5 being connected at their opposite ends by a back wall 6, thus defining a rectangular socket 7 85 adapted to receive and surround the picker stick 1 and to be slid downwardly on the same to the desired location to aline with the shuttle (not shown). The said frame or holder is adapted to be held in such a 90 position by a set screw 8 having threaded engagement with a suitable aperture in the back wall 6 of the socket, the said set screw 95 impinging against the rear face of the

picker stick. The lower edges of the rear side walls 5 are preferably slightly tapered towards the back wall 6. Any other form of fastener may be substituted for the set 5 screw.

Adapted to be fitted between the spaced, open-ended side walls 3 and to be introduced at the open end thereof, are a plurality of fillers or impact members composed of 10 leather, rawhide, fibres, rubber, felt or other suitable material. These fillers are made of a thickness about equaling that of sole leather, and each comprise a rectangular body portion 9 of a width to fit snugly between the front side walls 3 and to be frictionally engaged between the same, the said body portions 9 being somewhat higher than the said side walls, and having at their corners outstanding lugs 10 formed integrally 15 with the same and adapted to bear above and below the upper and lower edges respectively of said walls, as clearly shown in Figure 1 of the drawing, to rigidly hold the same in position, one upon the other, within 20 the space between the walls 3, the outermost filler being in position to contact with the nose of the shuttle, in the usual manner. Each filler is substantially I-shaped.

The rear wall 4 is provided at its top and 30 bottom edges with integral ears 4^a having suitable apertures for the reception of split keys 11, which also traverse apertures 9^a formed centrally near the top and bottom of each filler 9 and so located as to align with the apertures of the ears 4^a. The loop of 35 the split key or cotter pin is adapted to bear against the rear face of the ears 4^a, and the prongs are bent oppositely against the front face of the outermost filler to hold the entire 40 series in place, the location of the pins being such as to be out of the path of the nose of the shuttle.

When the outermost filler has become 45 worn by the pointed end of the shuttle forming a conical opening in the same, it is only necessary to reverse the fillers, or to place a rear one in front, or to discard the worn one and replace the same by a new one, which operation may be quickly accomplished 50 by stopping the machine only for a few moments, thus resulting in a great saving. It will be seen that the filler members are held in position in the frame or holder by the cotter pins 11 and that the impact of 55 the fillers with the end of the shuttle assists in holding them in place.

The modified form of the invention illustrated in Figures 5, 6, 7 and 8 is adapted for use in a loom wherein the picker, while actuated by the picker stick, in the usual manner, is further provided with a guiding means to insure the picker moving bodily in a horizontal direction.

A holder frame 12 formed of a metal 65 casting, preferably, is provided, near one

side, with a rectangular, vertically disposed opening 13 for the passage of the picker stick 14 which may be of the usual construction and operated in the usual manner, the opening being larger than the stick to allow the latter to oscillate. At one side of the opening 13 the holder is provided with a tubular bearing bore or passage 15 extending from front to rear of the holder and adapted to slide back and forth on a horizontally disposed guide bar 16 suitably secured to and forming part of the loom structure. 70

At the side of the picker stick opening 13 opposite the guide rod bearing 15, the frame 12 is provided with a horizontal, transverse extension 17 comprising a filler-holder, open at the front end directed towards the shuttle and open at the top and bottom, the outer wall 18 being connected to the body portion 85 of the frame by a rear wall 19 which is provided on its upper and lower edges with integral, apertured ears 20 similar to the ears 4^a of the first described form of the invention. 90

The opposed inner and outer faces of the seat defined by the body of the frame and the outer wall 18 are slightly dove-tailed as shown in Figure 8 and are adapted to receive between them the fillers 21 in the same 95 manner as heretofore described, the fillers being adapted to be expanded laterally to fill the dove-tail recess as they are effected by the repeated blows of the shuttle.

The fillers 21, which are formed of any 100 of the mentioned materials, are provided with outstanding lugs 22 at their upper and lower corners, which rest against the upper and lower edges of the body of the frame and the outer wall 18 and prevent any vertical movement of the same in the holder and the said fillers are further provided with apertures near their top and bottom edges, 105 said apertures being in alignment with the apertures of the ears 20 when the fillers are seated and adapted to receive split keys or cotter pins 23 to hold the fillers from forward movement in their seats.

The first described form of the invention is used in looms where the oscillating picker 115 stick is in the path of movement of the shuttle and carries the fillers directly in front of the same, while the form last described is adapted for use in connection with looms wherein the picker stick is located at 120 one side of the shuttle and between the same and the horizontal guide bar, as shown, but it will be seen that both forms embody the same features or elements for attachment to the picker stick, to be actuated thereby, and 125 having vertically disposed fillers carried by the frame in such manner as to expose the foremost filler to be engaged by the shuttle, the said fillers being readily interchanged or renewed. 130

From the foregoing, it will be seen that a simple, cheaply manufactured and easily installed picker for looms has been provided, which may be applied to any picker stick, 5 and that the same may be quickly renewed at any time by the simple replacement of the filler members, which may be cheaply manufactured and sold at a low cost.

What is claimed is:—

- 10 1. A picker for looms comprising a frame or holder provided with spaced, vertically disposed walls joined at their rear edges by a transverse wall having an apertured lug or ear at its top and bottom edges and defining a filler seat, said frame having a vertically disposed picker stick opening passing entirely through the same adjacent to the filler seat, and a plurality of fillers fitting in the seat and extending to the front edges of 15 the spaced walls, said fillers having outstanding corner lugs bearing on the top and bottom edges of the spaced walls to prevent vertical displacement of the same, each filler being substantially I-shaped.
- 20 2. A picker for looms comprising a frame or holder formed to provide spaced side walls, a transverse wall connecting the side walls at one end, a vertically disposed socket adapted to surround a picker stick and hav-

ing a fastening means for the same, and a plurality of fillers equal in width to the space between said spaced walls and adapted to snugly fit between and extend above and below the same and bear against the transverse wall, said fillers each having outstanding lugs at each corner to overhang and abut against the upper and lower edges of the spaced side walls.

3. A picker for looms comprising a frame or holder formed to provide spaced side walls, a transverse wall connecting the side walls at one end, perforated lugs extending upwardly and downwardly from the top and bottom edges of the transverse wall, a vertically disposed socket adapted to be traversed by a picker stick, and a plurality of fillers adapted to fit between and extend above and below the spaced walls of the holder and having recesses in their side edges for the reception of the same, said fillers being provided with apertures to align with the apertures of the said lugs, and fastening pins or keys engaging the ears and apertures in the fillers to hold the fillers in place.

In testimony, that I claim the foregoing as my own, I have hereto affixed my signature.

HERBERT IRVING EMMONS.
